MUSIC INSTRUCTION TOY

William M. Jenkins, 321 E. 43rd St., New York, N.Y.

Filed July 20, 1959, Ser. No. 56,843

Term of patent 7 years

(Cl. D25—1)

FIG. 1.

FIG. 2.

FIG. 3.

The dominant features of my design reside in the portions shown in full lines.

I claim:

The ornamental design for a music instruction toy, substantially as shown and described.
